UNITED STATES PATENT OFFICE.

JOSHUA GOODCHILD, OF PHILADELPHIA, PENNSYLVANIA, ASSIGNOR OF ONE-HALF TO
FRANK X. MATHIS, JR., OF PHILADELPHIA, PENNSYLVANIA.

REFRIGERATOR.

945,778.

Specification of Letters Patent. Patented Jan. 11, 1910.

Application filed February 17, 1909. Serial No. 478,372.

To all whom it may concern:

Be it known that I, JOSHUA GOODCHILD, a citizen of the United States, residing at Philadelphia, in the county of Philadelphia and State of Pennsylvania, have invented 5 certain new and useful Improvements in Refrigerators, of which the following is a specification.

My invention relates to improvements in 10 refrigerators, and more particularly to an improved cold storage apparatus, designed primarily for the keeping of meats in meat stores, and which will economize ice and secure a temperature below freezing to form 15 ice of its own.

A further object is to provide improvements of this character with a series of cylindrical tanks to contain cracked ice and brine, which will cause a frost or ice covering to 20 form around the outside of the tanks and reduce the temperature in the refrigerator to as low a point as may be desired.

A further object is to provide improvements of this character with improved means 25 for agitating or stirring the interior of the said tanks, improved means for draining the tanks and provide an improved pickling tank in which all of the first mentioned tanks are located to receive the low temperature 30 from said tanks, as well as from ice and brine contained in the pickling tank.

With these and other objects in view, the invention consists in certain novel features of construction, and combinations and arrangements of parts as will be more fully hereinafter described and pointed out in the 35 claims.

In the accompanying drawings, Figure 1, is a perspective view illustrating my improvements. Fig. 2 is a fragmentary view 40 in section through the wall of the apparatus. Fig. 3, is a view in vertical longitudinal section. Fig. 4, is a view in horizontal cross section. Fig. 5, is a view similar to Fig. 3, 45 but taken at a point nearer the front of the refrigerator, and Fig. 6, is a view in vertical cross section.

1 represents the casing or boxing of my improved refrigerator, which is made preferably of two thicknesses of wood, with a filling of paper or other insulating sheeting as shown in Fig. 2, to reduce the interchange 50 of temperatures between the interior in the refrigerator and outside air to a minimum.

55 The refrigerator is divided by a horizontal

partition 2, into a small upper compartment 3, and the lower main compartment 4. Access to this upper compartment is had through an opening in the front, normally closed by hinged doors 5, and hinged doors 6 60 are provided at both sides of the refrigerator and may be of any desired form, having transparent or opaque panes as may be desired.

Secured in the receptacle at a point removed from the bottom thereof, and extending longitudinally throughout the refrigerator, is a board or timber 7, and a rectangular metal tank 8 is located on the bottom of the refrigerator, and extends from the front of 70 the refrigerator backward to the rear edge of the said board or timber 7, and constitutes a pickling tank as will hereafter appear.

The board or timber 7 and the partition 2 75 are provided with aligned circular openings in which cylindrical tanks 9 are supported. I have illustrated five of these tanks, but of course am not limited in their number. These tanks are adapted to contain cracked 80 ice and brine, and are each drained through a common pipe 10, which projects outside of the refrigerator, and is provided with a drain cock 11. In all of these tanks I provide rotary stirrers or agitators 12, which latter 85 comprise a central rod or shaft 13, having a thrust bearing 14 in the bottom of the tank, and made angular at its upper end, which projects through the removable cap or closure 15 at the top of the tank and into the 90 compartment 3, so that an instrument can be readily inserted into the compartment 3 to turn the stirrers and agitate the contents of the tanks. The stirrers may of course, be made in various ways, but I have illustrated 95 one form in which the stirrers comprise blades to extend approximately throughout the length of the tank and connected to the center rod or shaft by cross rods 16.

Provision may be made for the supporting of meat in various ways, but a preferred form is to provide a series of longitudinal horizontal bars 17 having hooks 18 thereon, so as to permit a large amount of meat to be hung in the compartment, but I of course 100 do not limit myself to any particular manner of supporting the meat.

The tank 8 as above described is intended as 110 a pickling tank, and is adapted to contain ice and brine up to the desired level, and to

receive the meat to be pickled in cans or receptacles 19, and removable covers 20, close the upper ends of the tanks to keep out the dirt. It is obvious that various other things 5 which it is desired to cool or freeze may be placed in the brine in tank 8, such, for example, as cans of milk to be cooled, or cans of water to be cooled or frozen.

Between the tank 8 and the rear wall of 10 the refrigerator, a space is provided in which receptacles 21 may be located to contain meat of various kinds, and the entire interior space of the refrigerator may of course be utilized in various ways for refrigerating purposes.

In operation all of the tanks 9 are filled with cracked ice and brine, and almost immediately frost will begin to form around the tanks, and the longer the device is in 20 use, the thicker and heavier will become the coating of ice around the outside of the tanks, reducing the temperature in the refrigerator as low as it is safe to keep the meats. The tank 8 is also to contain ice and 25 brine to the desired level, and by regulating the quantities of ice and brine in the several tanks, the temperature can be regulated to exactly suit conditions.

It will be understood that the connection 30 between the bar or timber 7 and partition 2 and the several tanks 9, is an approximately air tight juncture, and when the covers 20, which are also approximately air tight, are in position, there are three chambers formed, 35 which are for all practical purposes air tight with relation to each other, so as to prevent an interchange of temperatures, and allow free access to the intermediate chamber where the meat and other articles are stored 40 without affecting, to any appreciable extent, the temperature of the brine tank below, and access may be had to the upper ends of the tanks 9 to charge them without affecting the temperatures of either of the chambers below.

Various slight changes might be made in the general form and arrangement of parts described without departing from my invention, and hence I do not restrict myself

to the precise details set forth, but consider 50 myself at liberty to make such changes and alterations as fairly fall within the spirit and scope of the claims.

Having thus described my invention what I claim as new and desire to secure by Letters Patent is:

1. In a refrigerator, the combination with a box or casing, of two approximately air-tight horizontal partitions dividing said box or casing into a lower brine tank or chamber, an intermediate refrigerating chamber, and upper feeding chamber, one or more tanks projecting into all of said chambers and adapted to be supplied with a refrigerant through said feeding chamber. 65

2. In a refrigerator, the combination with a box or casing, of two horizontal partitions in said casing having registering openings and forming an upper feeding chamber, a lower brine tank or chamber, and an intermediate provision chamber, refrigerant tanks located in said registered openings, said partitions normally preventing any circulation of air between the chambers, said refrigerant tanks passing through the intermediate chamber and projecting into the upper and lower chambers, and being provided with removable covers in the upper chamber. 70 75

3. In a refrigerator, the combination with a box or casing, of a horizontal partition spaced from the top of the casing and preventing circulation of air between the upper chamber formed thereby and the chamber below, a brine tank in the bottom of the box or casing, an approximately air tight partition above said brine tank, removable covers in said last mentioned partition, and refrigerant tanks projecting through both of said chambers and into the brine tank. 80 85 90

In testimony whereof I have signed my name to this specification in the presence of two subscribing witnesses.

JOSHUA GOODCHILD.
